TRAFFIC SIGNAL HEAD

William B. King, 922 Audubon Drive, Clayton, Mo.

Filed July 13, 1964, Ser. No. 80,812

Term of patent 14 years

(Cl. D72—1)

FIG. 1.

FIG. 2.

FIG. 3.

FIG. 4.

FIG. 5.

FIG. 1 is a front elevation of a traffic signal head, embodying my new design;

FIG. 2 is a side elevation;

FIG. 3 is a rear elevation;

FIG. 4 is a top plan view; and

FIG. 5 is a bottom plan view thereof.

I claim:

The ornamental design for a traffic signal head, substantially as shown.
